FISHING LURE

James M. Kemp, P.O. Box 5559,
Phoenix, Ariz. 85010

Filed Mar. 30, 1973, Ser. No. 346,463

Term of patent 14 years

Int. Cl. D22—05

U.S. Cl. D22—27

FIG. 1 is a front perspective view of a fishing lure;
FIG. 2 is a perspective view of the fishing lure shown
in FIG. 1 looking at it from the left; and

FIG. 3 is a front perspective view of the fishing lure
shown in FIG. 1 illustrating more details of the structure.

I claim:

The ornamental design for a fishing lure, as shown.
